FIG. 1.

FIG. 2.

FIG. 3.

FIG. 4.

FIGURE 1 is a front elevation showing our top toy;
FIGURE 2 is a top plan view of the uppermost rotating member;

FIGURE 3 is a top plan view of the middle rotating member; and

FIGURE 4 is a top plan view of the bottom rotating member.

The rear elevation is essentially a mirror image of the front elevation and the bottom plan views of the rotating members are essentially identical to the top plan views shown in FIGURES 2, 3 and 4.

We claim:

The ornamental design for a top toy, as shown and described.
